UNITED STATES PATENT OFFICE.

GEORGE EDMOND DENMAN, OF FRUITVALE, CALIFORNIA.

LIQUID-FUEL BURNER.

1,086,998.

Specification of Letters Patent. Patented Feb. 10, 1914.

Application filed January 2, 1913. Serial No. 739,634.

To all whom it may concern:

Be it known that I, GEORGE EDMOND DENMAN, a citizen of the United States, and a resident of Fruitvale, in the county of Alameda and State of California, have invented a new and Improved Liquid-Fuel Burner, of which the following is a full, clear, and exact description.

This invention relates to burners through which the liquid fuel is forced out into a fine, evenly subdivided spray, the particles of which are made to intermingle with the fluid, by means of which the atomizing of the liquid fuel is obtained, and has reference more particularly to the class comprising an inner and an outer casing having independent inlets, one for fuel and the other for the compressed fluid, and a tip body secured to both of said casings and through which the liquid fuel is forced by means of the compressed fluid.

The object of the invention is to provide an inexpensive, simple and efficient burner which can be easily cleaned, repaired and its wearing parts easily assembled.

A further object of the invention is to provide a burner in which different tips can be used.

Reference is to be had to the accompanying drawings forming a part of this specification in which similar characters of reference indicate corresponding parts in all the views.

Figure 1 is a longitudinal central section of an embodiment of my invention; Fig. 2 is a horizontal central section through the tip body; Fig. 3 is a modified form of the tip body; Fig. 4 is a perspective view of the cap; Fig. 5 is a perspective view of the distributing cup partly cut away to show the distributing orifices; Fig. 6 is a perspective view of the central dividing washer; and Fig. 7 is a perspective view of the upper and lower spray-forming cut-away washers.

Referring to the drawings, 10 represents a cross member having a through bore 11, a compressed fluid inlet 12 leading to the through bore 11, and a liquid fuel inlet 13 lying opposite the fluid inlet 12, both perpendicular to the bore 11. The fuel inlet 13 leads to a central bore 15 provided with a body portion 14 extending from the center of the cross member toward one end of the same, and it is concentric with the bore 11. In the end of the bore 11 lying opposite the central body portion 14 is a threaded cap

16 which carries centrally a plunger 17 projecting through the cap. The plunger 17 is, at the inner projecting end, provided with a valve head 18 normally forced against the adjacent end of the bore 15 by means of a coil spring 19 positioned on the plunger 17. By pulling on the exteriorly projecting end of the plunger 17 the spring 19 is compressed and the valve head 18 of the plunger 17 is drawn away from the through bore 15 thereby establishing communication between the bore 11 and the bore 15.

Connected exteriorly to the cross member 10 by means of a union 20 is a nipple 21 axial with the bore 11 and at the end toward which the central body portion 14 extends. A tubular member 22 is secured centrally to the body portion 14 axially with the bore 15, and the said tubular member 22 projects out at the opposite end of the nipple 21. Secured directly to the tubular portion 22 and to the nipple 21 by means of a union 23 is a plug 25 having a central bore 24 and a plurality of passages 26. A cap 27 is screwed to the other end of the plug 25 and it has a through bore substantially equal to the end bore of the plug 25. Threaded into the central bore 24 of the plug 25 is a tip body 28, having a shoulder 29 abutting snugly against the free non-threaded end of the cap 27. By screwing off the cap 27 from the plug 25, the abutting joint between the tip body and the cap is made tight. The tip body 28 has a semi-spherical end portion provided with a slit 30 connected to the central passage 31 of the tip by means of a flattened passageway 32 converging from the slit toward the bore. The portion of the tip lying in rear of the shoulder 29 is conical, and its slope is parallel with the slope of the passage 32. A pair of apertures 33 is provided in the cone-shaped portion of the tip opposite each other and converging toward the end of the passage 32 and terminating in the flattened portion of the passage. Another pair of passages 34 is provided in said cone-shaped portion opposite each other and at right angles to the passages 33 and terminating in the beveled sides of the passage 32. As the passages 33 and 34 lie exteriorly on the same circle on the cone-shaped portion of the tip they terminate inwardly at different distances from the end of the tip due to the fact that one pair enters the flattened portion of the passage 32 while the other pair

enters the beveled portion. This difference in termination affords a better mixture of the fuel and the compressed fluid in the passage 32 before the spray is formed. Due to the inclined position of the passages 33 and 34 no back pressure is formed in the central passage 31 but instead a suction is created due to the inclination of the passages toward the end of the tip.

10 In the modified form, the tip body or nozzle 35 is provided with a stem 47 screwed into the bore 24 whereby the body portion is made to bear against the end of the cap 27 so as to prevent leakage between the body of the tip and the cap. The body 35 has also a central extension 36 perpendicular to the axis of the burner body and has also thereon a central threaded shank 37. The central bore 38 of the nozzle extends into the shank 37 substantially as far as the threaded portion where it has an outlet to the lateral surface of the shank in a direction away from the stem 47 of the burner and substantially parallel with it. The body 35 is also provided with a plurality of through bores or passages 39 surrounding the central bore 38 and intended to convey the compressed fluid from the cap end to the end of the central projection 36, where the bores or passages are interconnected by a groove 40. Engaging the shank 37 and resting on the central projection 36 is a washer 41 having a cut-away portion 41', the cut-away portion of the washer lying in alignment with the outlet of the bore 38. Over the washer 41 and on the shank 37 is a circular washer 42 and on this washer is a washer 43 similar to the washer 41, with its cut-away portion 43' lying above the cut-away portion 41' of the washer 41. The size of the cut-away portion determines the width of the spray. Directly over the washer 43 on the shank 37 is a cup 44, the hollow of which is below the outlet of the bore 38 in the shank and the edge of the cup above the outlet. A plurality of apertures 45 are provided in the bottom of the cup 44 and disposed above the cut-away portion 43' of the washer 43, so that the oil running through the bore 38 drips from the orifices 45 onto the washer 42, from where it flows on to the lateral surface of this washer and has a tendency to drip over the lower edge of the washer 42, from where the compressed fluid passing through the cut-away portion 41' carries it away in a spray. To maintain the washers and cup in place a cap 46 is screwed on the shank 37 against the edge of the cup 44 thereby closing the hollow of the cup and also forcing the same against the washers 43, 42 and 41, which in turn are forced against the central body 36.

The compressed air or steam admitted to the inlet 12 fills the space surrounding the inner passage 22 through which the oil flows

when admitted through the inlet 13. The oil flowing through the central passage when reaching the apertures 34 is directed by the compressed fluid due to the inclination of the apertures toward the end of the passage 32 across the apertures 33, where again the same compressed fluid forces them against the flattened portion of the tip end, thereby making a perfect mixture before the same is forced out in a spray.

75
In the modified form of the tip body the oil dripping onto the circular washer 42 spreads on the same as far as the cut-away portion 43' permits and then over the washer where it is met by the compressed fluid coming out from the passages 39, and thereby atomizes and forms into a spray, the width of which is substantially that of the cut-away portions of the washers 41 and 43.

85 It can be easily seen that when steam is used the heat of the steam surrounding the central passage 22 of the burner body will raise the temperature of the oil flowing through the passage which will be very beneficial in case the oil is dense.

90 In the modified form of my tip the portion subjected to maximum wear is the circular washer 42, which can be easily replaced, as can be seen from Fig. 3.

95 Having thus described my invention, I claim as new and desire to secure by Letters Patent:

1. A device of the class described, comprising an outer casing, an inner casing, independent inlets to said casings, a tip body connected at one end to both of said casings having a lateral extension, and a threaded shank on said extension, said tip body having a central passageway leading from said inner casing within said shank and terminating in a lateral outlet passage and a plurality of passages surrounding said central passage leading from said outer casing to the surface of said lateral extension, a distributing cup on said shank communicating with said outlet passage, and washers intermediate said lateral extension and said cup having means for forming a spray by the liquid flowing from the cup and the compressed fluid flowing from the end of the central portion.

110
2. A device of the class described, comprising an outer casing, an inner casing, independent inlets to said casings, a tip body connected at one end to both of said casings having a central extension perpendicular to said casings, and a threaded shank on said extension, said tip body having a central passageway leading from said inner casing within said shank and terminating in a lateral outlet passage and a plurality of passages surrounding said central passage leading from said outer casing to the surface of said central extension and a groove connecting said surrounding passages, a cup on

5 said shank communicating with said outlet passage on the shank and having distributing apertures in the bottom thereof, a plurality of washers between said cup and said 10 central extension, and a threaded cap on said shank closing said cup and maintaining same on said washers in a predetermined position, certain of said washers below said cup and above said central extension having 15 cut-away portions in alinement with each other and under said distributing apertures of said cup.

3. A device of the class described comprising, an exterior tubular member and an 15 interior tubular member; a plug at one end secured to said exterior and said interior tubular members, said plug having a central passage communicating with said inner tubular member and a plurality of passages 20 surrounding said central passage communicating with said exterior tubular member; a

tip body secured to said plug and having a central passage communicating with said central passage of said plug and a plurality of passages surrounding said central passage communicating with said surrounding passages in said plug, said passages in said tip body having a common outlet at the tip end, said central passage of said tip having an outlet above said common outlet; and a 25 cross member secured to said exterior and interior members at the end opposite said plug and having independent inlets to said exterior and interior tubular members.

In testimony whereof I have signed my 35 name to this specification in the presence of two subscribing witnesses.

GEORGE EDMOND DENMAN.
